FLUID CONTROL VALVE MECHANISM FOR
FLUID PRESSURE OPERATED ROTARY OR
TURRET TYPE LAUNDRY PRESSES

Ronald Percy Gudgeon, Luton, England

Application February 27, 1948, Serial No. 11,802
In Great Britain January 5, 1945

1 Claim. (Cl. 38—22)

1

The present invention relates to the pressure control of laundry or other presses, and more particularly though not exclusively to that type of press in which a pair of tables rotate about a centre column into position below a press head.

Normally, in the known types of laundry press the fluid pressure for operating the arm lifting the table to the head is operated by a tappet mounted on the arms supporting the tables and which when the table arrives below the pressure head strikes and depresses a plunger which operates a valve to expose the ram cylinder to pressure. When it is desired to release the table, a foot lever is depressed which action opens a second valve permitting the exhausting of the pressure and consequential descent of the table. After exhaust from the ram cylinder and descent of the table, the tables are once more rotated about the column, thus closing the control valve to the ram cylinder until the other table comes into position and its tappet strikes the plunger controlling said valve.

An object of the present invention is to provide mechanism in which not only are the aforesaid valves all arranged in one valve housing but the action of opening and closing the main control valve and the exhaust valve is automatic with rotation of the tables about the column.

Broadly the invention comprises a fluid pressure control comprising a valve member adapted to be reciprocated in a valve housing, ports leading into said valve housing connecting with conduits leading to exhaust and to an operating ram or other point respectively, said ports being so positioned with respect to the valve member that with the said member at one end of its stroke the fluid pressure medium which is led into the valve housing at a convenient point is fed to the ram or other desired point and with the said member at the other end of its stroke the supply of fluid pressure medium is shut off and the ram cylinder or other point is connected to the exhaust port.

According to the present invention the fluid pressure control for elevating the table of a laundry or other press of the type in which a table or tables is or are rotated about a centre to be brought underneath and away from a press head, for instance as illustrated in my simultaneously filed application now issued as Patent No. 2,609,624, dated September 9, 1952, comprises a valve member adapted to be reciprocated in a valve housing, ports in the wall of said valve housing connecting with conduits leading to exhaust and to the table operating ram respectively,

said ports being so positioned with respect to the valve member that with the said member at one end of its stroke the fluid pressure medium which is led into the valve housing at any convenient point is fed to the table ram and with the said member at the other end of its stroke the supply of fluid pressure medium is shut off and the table ram exhausted.

Conveniently the position of the valve member is selected automatically by the position of the table or tables of the press. Manual control means are also provided for moving the valve member from the pressure delivery position to the exhaust position, the valve member being exposed continuously to the pressure of the fluid pressure medium so that it tends to move to that end of its stroke which connects the pressure supply to the table ram cylinder.

The invention will now be described with reference to the accompanying drawings in which:

Figure 1 shows in side elevation partly in section a fluid pressure control according to the present invention applied to a twin table laundry press;

Figure 2 shows on an enlarged scale a section of the control unit;

Figure 3 shows in section an alternative construction of control unit; and

Figure 4 shows an application of this unit to a twin table rotary laundry press.

Referring to the drawings a pair of tables (not shown) are mounted upon a centre column 1 in known manner to be positioned in turn below a press head (also not shown). Column 1, representative of a rotative part of the table structure so far as involved herein, carries a collar member 2 the upper surface of which forms a cam surface 3 upon which rides a cam roller 4, this cam roller being a specific form of cam rider generally. The roller 4 is carried by one arm 5 of a three-armed spider lever 6 pivoted to a stationary part of the press at 7. A second arm 8 is connected by a rod 9 to a foot lever 10 which is spring loaded so as to urge the roller 4 into engagement with the cam surface 3. The third arm 11 of the spider carries a tappet member 12 which bears against a valve spindle 13 the lower end of which is formed into a double valve member 14 sliding within a valve housing 15. The cam and cam rider constitute an indexing device with spider lever 6, tappet 12 and foot lever 10 with its spring loading constituting valve-operating means.

The valve housing 15 is provided at its lower end with a port 16 which is connected via suitable conduit 17 to a source of fluid pressure for

example compressed air. To adjust the rate of supply of the compressed air a needle valve control 18 is provided, adjustment of which controls the speed at which the table lifts. In the wall of the valve housing 15, intermediate the ends of the stroke of the valve member 14, there is provided a plurality of ports 19 radiating as an annular series from the interior of said valve housing 15, said ports leading to an annular duct 20 surrounding said series and connecting with a conduit 21 leading to the cylinder of pressure ram 22 which operate to elevate the table, when it is in position beneath the press head.

The cam surface 3 is provided with a pair of diametrically opposite arcuate recesses 23, 23 into which the roller 4 drops these recesses being so positioned that when the table arrives below the press head the roller 4 drops into the recess 23. The valve member 14 being under constant pressure from the compressed air supply is, when the roller 4 drops into the recess 23, permitted to move under the pressure up the valve housing 15. This movement from the position shown by broken line in Figure 2 to that shown by solid line in Figures 1 and 2, uncovers the ports 19 and connects the ram cylinder 22 with the pressure supply and the table is lifted into contact with the press head for the pressing operation. This condition pertains until the pressing operation is completed whereupon the operator depresses the foot pedal 10 which action depresses the tappet 12 and moves the valve member 14 down the valve housing 15 to the position shown by broken lines in Figure 2. In this position the compressed air supply is cut to the table ram 22 and the residual pressure in the ram cylinder is led off to exhaust via the same ports 19 through exhaust flutes 14 which may conveniently be formed in the guideway 25 for the valve spindle 13. When the table is free from the press head the operator turns or rotates the tables to bring the other table beneath the press head and this movement moves the recess 23 from beneath the roller which now rests upon the cam surface 3 and the operator can release the foot pedal 10 and the cycle is once more repeated.

Referring to Figure 3 thus drawing shows a slightly modified form of control unit. In this construction the valve spindle 13 has a hollow bore 13a to which communication is made at two positions by radial ports 26 and 27. In the position shown which is the exhaust position the port 29 which leads to the table ram is connected to the centre bore 25 by the ports 27 and the residual pressure exhausted via the radial ports 26 to an annular duct 28 connected to exhaust. On relief of pressure on the head of the spindle 13 the valve member 14 is moved under the action of the compressed air supply to the position shown in chain line. This disconnects the port 28 from the exhaust and connects the port with the compressed air supply.

This valve is shown applied to a rotary twin table laundry press in Figure 4. In this construction the roller 4 follows a cam surface on the edge of the collar 2, corresponding recesses 23 being provided. In this construction a pivoted two-arm lever 29 is employed carrying the roller on one arm and a tappet 30 on the other arm which tappet bears against the spindle 13. This arm carries a lug 31 to which a link 35 is pivoted and is connected to the foot lever. The exhaust from the ram cylinder is led off through an exhaust baffle 34. The operation of this pressure is exactly the same as that of the press shown in Figures 1 and 2.

What I claim is:

In a fluid pressure operated rotary or turret type laundry press, a fluid control valve mechanism comprising a valve member adapted to be reciprocated, a valve housing containing said valve member reciprocably therein, said valve housing having a fluid pressure supply port and a fluid pressure exhaust port leading into the housing next opposite end portions thereof and having an intermediate port and conduit connected thereto, an operating ram and cylinder therefor in said press, the said conduit leading to said ram cylinder, said valve member and ports being so positioned with respect to each other that the said member is constantly urged to one end of its stroke by the fluid pressure medium to place the intermediate port in communication with the supply port for supplying fluid pressure medium to the ram cylinder, manually operable means for moving said valve member to the other end of its stroke against the pressure of the fluid medium to place the intermediate port in communication with the exhaust port whereby the ram cylinder is connected to exhaust, and means actuated by rotation of the press adapted also to move the valve member to said other end of its stroke and to render ineffective the same manually operable means.

RONALD PERCY GUDGEON.
